UNITED STATES PATENT OFFICE.

FREDERICK A. FAULHABER, JR., OF EAST ORANGE, NEW JERSEY.

ELECTRIC-LAMP SOCKET.

Application filed September 11, 1924. Serial No. 737,093.

To all whom it may concern:

Be it known that I, FREDERICK A. FAULHABER, Jr., a citizen of the United States, residing at East Orange, in the county of Essex and State of New Jersey, have invented certain new and useful Improvements in Electric-Lamp Sockets; and I do hereby declare the following to be a full, clear, and exact description of the invention, 10 such as will enable others skilled in the art to which it appertains to make and use the same, reference being had to the accompanying drawings, and to characters of reference marked thereon, which form a part of this 15 specification.

This invention relates, generally, to improvements in socket connections for incandescent electric lamps.

The invention has for its principal object 20 to provide a very simple, cheap and durable construction of socket connection having a novel arrangement and construction of contact devices for engaging the terminal electrodes of the lamp base, when the latter is 25 inserted in the socket, together with a novel arrangement whereby both the lamp itself and the terminal contact of the electric service wire are interlocked with the socket structure so as to not only assure a good 30 mutual contact, which is undisturbed by vibrations or jars, but also whereby said wire terminal contact is so interlocked with the socket structure that accidental displacement thereof is prevented.

Another object of this invention is to provide a novel construction of socket connection which may be utilized in a direct connected circuit arrangement, or which, by a simple addition, may be provided with a 35 self-contained cut-off switch means for providing individual control of the lamp supported in the socket connection.

Other objects of this invention, not at this time more particularly enumerated, will be 40 clearly understood from the following detailed description of the same.

The invention is clearly illustrated in the accompanying drawings, in which:—

Figure 1 is a side elevation of the novel 45 socket connection with a lamp in place, all

disposed for a direct connected circuit arrangement; Figure 2 is a longitudinal vertical section of the socket connection, taken on line 2—2 in Figure 1; Figure 3 is another longitudinal vertical section, taken on line 3—3 in Figure 2; Figure 4 is another side elevation, taken in a plane at right angles to the plane of Figure 1; Figure 5 is a horizontal section, taken on line 5—5 in Figure 1; Figure 6 is a longitudinal vertical section, similar to that shown in Figure 3, but illustrating the addition of a slide member arranged to provide the socket connection with a self-contained cut-off or control switch; Figure 7 is a horizontal section taken on line 7—7 in said Figure 6; and Figure 8 is a perspective view of the switch slide member detached from the socket connection.

Figure 9 is a view showing the provision 70 of a hood in connection with the novel socket device, thus adapting the latter for use as an instrument board or dash lamp fitting; Figure 10 is a vertical longitudinal section, taken on line 10—10 in Figure 9; 75 and Figure 11 is a horizontal section on an enlarged scale, taken on line 11—11 in Figure 10.

Similar characters of reference are employed in all of the hereinabove described 80 views, to indicate corresponding parts.

Referring now to the drawings, the socket is formed out of a sheet metal blank which is rolled into tubular form to provide a socket body or ferrule 12, provided in opposite portions of its walls with bayonet slots 13 opening at the outer end of said tubular socket body or ferrule 12. Integrally connected with the inner end of said tubular socket body or ferrule 12 are a pair of longitudinally extending diametrically opposed leg or standard members 14, the latter possessing, adjacent to their juncture with the socket body or ferrule 12, inwardly off-set portions 15 providing stop-shoulders from 90 which the major portions of the leg or standard members extend, to thus form a socket standard of reduced width. The lower end of each leg or standard member is provided with an outwardly turned foot- 100

piece 16, preferably projecting at right-angles to the leg or standard members. The free ends of said foot-pieces 16 are downwardly turned to provide clenching lugs 17 for insertion through the wall 18 of a base upon which the socket connection is to be mounted, said clenching lugs being turned over against the rear side of said wall 18 to secure the socket connection, as supported by the leg or standard members, in desired fixed position.

The reference character 19 indicates a contact coupling plate, the same being made of suitable insulating material, such as hard-rubber, fibre, condensite, or similar material. Said contact coupling plate 19 is mounted for vertical movement on the leg or standard members 14 by providing in the body of said contact coupling plate a pair of slots or openings 20 (see Figure 5), corresponding in relative disposition and in cross-sectional shape to the relative disposition and cross-sectional shape of said pair of leg or standard members 14. When making up and assembling the socket structure, said contact coupling plate 19 is slid upon the leg or standard members 14 before forming the foot-pieces 16 in connection with the latter. The upward movement of the contact coupling plate 19 will be limited by the engagement thereof with the stop-shoulders formed by the inwardly off-set portions 15 at the upper ends of said leg or standard members 14. Arranged about the leg or standard members 14, intermediate said contact coupling plate 19 and the foot-pieces 16, is a compression spring 21 which exerts a normal upwardly thrusting pressure upon said contact coupling plate 19, whereby, the same is yieldingly moved toward the lower end of the socket for purposes to be subsequently set forth. Said contact coupling plate 19 is provided with a central opening 22 axially alined with the interior of the socket body or ferrule 12. Said base wall 18 is also provided with an opening 23 in alinement with the opening in said contact coupling plate 19. Affixed to said contact coupling plate, so as to be disposed, preferably, upon its upper surface, is a yieldable retaining or coupling means, the same comprising a spring wire formation consisting of a wire body doubled upon itself to form a pair of laterally separated spring arms 24, disposed to extend diametrically across the face of said contact coupling plate 19, and thus arranged to cross the opening 22 of the latter. That portion of each spring arm 24, which crosses the said opening 22, is provided with an outwardly bowed portion thus providing a pair of opposed outwardly yieldable gripping jaws 25 alined with said opening 22. The spring arms 24 are fixed in operative attached relation to said contact coupling

plate 19, by providing notches in the periphery of the latter at diametrically opposite portions thereof, and then turning downward into said notches at one side of the plate the free extremities 26 at one end of the formation providing said spring arms, and clenching over portions 27 against the bottom of said plate 19, and, in like manner, turning downward into said notches at the opposite side of the plate the closed end or loop 28 of the wire formation providing said spring arms, all as shown in the drawings, or the formation may, be otherwise secured, in any convenient manner, to the said contact coupling plate 19.

The reference character 29 indicates an electric incandescent lamp for attachment or connection in the socket body or ferrule 12, the same having a base-portion provided with an external contact ferrule 30 having opposite laterally projecting locking pins 31, and, at the free end or extremity of said base-portion, having a central terminal contact or electrode 32 through which the current enters the lamp, to traverse the lamp filament, and then pass through the contact ferrule 30 to the ground formed by the lamp socket device. The service wire 33 through which current is delivered to the lamp, when the latter is mounted in the socket body or ferrule 12, is provided with a metallic and preferably cylindrical, terminal electrode 34, having a hollow rear end providing a receiving socket 35 in which the free end of said service wire 33 is inserted. The walls of said hollow rear end of said terminal electrode are inwardly depressed to provide an internal annular gripping ridge 36 for engaging and binding said wire 33 in mechanical and electrical coupled connection with said terminal electrode 34. The wire 33 may be coupled with said terminal electrode 34 in other ways, if desired. The free end of said terminal electrode 34 is preferably provided with a substantially conical contact point 37, and the body of said terminal electrode 34 is provided, in suitably spaced relation below said conical contact point 37, with an annular indentation or groove providing a lock means or seat 38. The service wire 33 and its terminal electrode 34 are operatively connected with the lamp socket device by inserting the same through the opening 23 of the base wall 18, to pass the terminal electrode upwardly between the leg or standard members 14, so that the free end of said electrode extends upwardly through the opening 22 of said coupling plate 19, and between the gripping jaws 25 of the spring arms 24, which yield to such passage until the annular lock means or seat 38 is encountered, whereupon the gripping jaws 25, under the inwardly moving tension of said spring arms 24, drop into said seat 38, thus firmly

and securely coupling said electrode with the coupling plate 19, with the contact point projected upwardly from the latter and disposed opposite the lower end of and axially aligned with the socket body or ferrule 12.

To insert the lamp 29 in the socket, the base-portion with its encircling contact ferrule 30 is entered in the free open end of the socket body or ferrule 12, in such manner that the locking pins 31 pass into the respective bayonet slots 13. As the lamp is pushed down into the socket body or ferrule 12, the central terminal contact or electrode 32 of the lamp is brought into engagement with the upwardly projecting contact point 37 of the service wire electrode, which is firmly coupled or held by the coupling plate 19. This engagement of the electrode 32 with the contact point 37 takes place before the locking pins 31 reach the bottom of the bayonet slots 13, and, consequently, as the lamp base moves further in to carry the locking pins into interlocked engagement with the bottoms of the bayonet slots, the wire terminal electrode 34 and coupling plate 19 to which it is secured are pressed downward against the tension of the compression spring 21. The increased tension thus produced in the compression spring 21 tends to strongly thrust upwardly against the coupling plate 19, whereby the contact point 37 of the wire terminal electrode 34 is firmly held in operative engagement or contact with the lamp contact or electrode 32, and at the same time the endwise pressure on the lamp itself tends to hold the locking pins 31 thereof in their operative interlocked relation to the bayonet slots 13 of the socket body or ferrule 12, all to the end that accidental displacement of the lamp or interruption of the normally closed contact between the lamp and service wire by reason of vibrations, jars or similar causes, is prevented. The wire terminal electrode 34 is also firmly and securely held against dislocation or separation from operative relation to the socket device by ordinary strains of vibration, jars, etc., because of the grip maintained thereon by the gripping jaws 25 as tensioned by the spring arms 24. If, for any reason, it is desired to remove or detach the wire terminal electrode 34 from the socket device, this may be accomplished by a rearward pull upon the service wire 33 of sufficient force to overcome the tension of the spring arms 24 so that the jaws 25 are thereby separated and outwardly moved from the lock means or seat 38 of said terminal electrode 34.

The above described arrangement is illustrative of the use of my novel socket device, when a direct connected relation of service wire to the lamp is desired. In many cases, however, it is desirable to provide a means directly related to or combined with the socket, whereby the lamp mounted therein

may be turned on and off at will. To this end my novel construction of socket is of such character, that by a simple addition, without necessity of altering the construction of the socket features in any way, I can provide the same with a novel slide switch means, whereby the lamp may be easily turned on and off at will, all of which is illustrated in Figures 6 to 10 inclusive of the accompanying drawings. The additional element, which provides the slide switch, consists of a flat elongated slide member 39, made of a suitable non-conductive or insulation material. This slide member 39 is diametrically disposed across the under or lower end of the socket body or ferrule 12, so as to extend between the leg or standard members 14, and so as to be interposed between the terminal contact or electrode 32 of the lamp and the contact point 37 of the service wire electrode 34. In order to maintain the slide member 39 in the desired diametrically disposed relation to the lower or inner end of the socket body or ferrule 12, the walls, at the lower margin of the latter, are indented to provide guide notches 40, which hold said slide member 39 against lateral displacement while permitting free longitudinal movements thereof. In order to limit the longitudinal movements of said slide member 39, the respective exterior ends thereof are provided with laterally enlarged heads or stops 41. The intermediate portion of said slide member 39 is provided with a metallic switch contact 42, which is longitudinally off-set, in one direction from the central point of said slide member, and which extends vertically through the body of the latter. This metallic switch contact 42 is preferably, but not necessarily, in the form of a hollow rivet. Preferably, the slide member 39 is further provided with an opening 43, providing on opposite sides of the same, seats or depressions respectively engageable by the lamp terminal contact or electrode 32 on the one or upper side and by the contact point 37 of the service wire electrode 34 on the other or underside. When the slide member is operatively assembled in the above described relation to the socket body or ferrule 12, it is interposed between the lamp terminal contact or electrode 32 and the contact point 37 of the service wire electrode 34. When thus disposed the upward moving pressure of the electrode 34 exerted by the upward thrust of the coupling plate 19 under the tension of the compression spring 21, maintains the slide member operatively engaged between said lamp terminal contact or electrode 32 and the contact point 37 of the service wire electrode 34. A longitudinal moving of the slide member 39, induced by pressing inwardly on one exterior end thereof, will

slide the member 39 in the direction of such applied pressure and will carry the metallic switch contact 42 into alignment between and into mechanical and electrical engagement with the lamp contact or electrode 32 and the contact point 37 of the service wire electrode 34, thus closing the circuit and permitting the operative flow of current from the service wire through the lamp; an opposite longitudinal moving of the slide member 39, induced by pressing inwardly the opposite exterior end thereof, will slide the member 39 in the opposite direction, so as to carry the metallic switch contact 42 away from mutual contact with and between the lamp contact or electrode 32 and the contact point 37 of the service wire electrode 34, and at the same time will interpose the insulative body of said slide member 39 between the latter electrodes, in alignment and in engagement with the surface depressions provided by the opening 43, thus interrupting the circuit and stopping operative flow of current from the service wire through the lamp.

The switch slide member 39 may be readily detached from operative relation to the socket device by depressing the coupling plate 19 against the tension of the spring 21, thus allowing the slide member to drop out of the guide notches 40, whereupon the same may be withdrawn from between the legs or standards 14. By a reversal of the described operations, the slide member 39 may be operatively assembled with the socket device.

It is frequently desirable, especially when the socket is mounted on an instrument board or dash, to provide a hood or shade in connection therewith, I have shown in Figures 9, 10 and 11 one arrangement for mounting such a hood or shade in connection with the lamp socket device. This arrangement comprises the provision of a hood base 44, the marginal portions of which are turned inwardly over its main body, as at 45, with the free edge portions thereof turned upwardly to provide an annular outwardly projecting flange 46. The main body is provided with a central opening or perforation 47, which is registered with the opening 23 in the wall 18, whereby the service wire and its electrode 34 may be inserted for connection with the socket. The base is further provided with suitably disposed openings or slots 48 (see Figure 11), through which may be inserted the clenching lugs 17 of the foot-pieces 16 connected with the leg or standards 14 of the socket device, whereupon the said clenching lugs 17 are passed through the wall 18 and clenched over, to thus not only fasten the socket device to the latter, but also to retain the base 44 both assembled with the socket device and attached to said wall 18,

all as shown in Figures 9, 10 and 11 of the drawings. The reference character 49 indicates a suitably shaped hood or shade member, having a light emitting opening 50 in its wall, said hood or shade member 70 being open at its bottom end. The open bottom end of said hood or shade member is telescopically engaged over the flange 46 of the base 44, being thus operatively supported in desired enclosing relation to the 75 socket device and the lamp mounted in the latter. If the socket device is provided with the slide-switch device, the walls of the hood or shade 49 are upwardly slotted, as at 51, to straddle the exterior ends of the switch 80 slide member 39, so that said respective exterior ends may be operatively exposed exteriorly of the hood or shade.

I am aware that some changes may be made in the arrangement and detail construction of the several parts of my novel socket device without departing from the scope of my invention as set forth in the foregoing specification and as defined in the appended claims. Hence, I do not limit 90 my invention to the exact arrangements and combinations of the various parts as above described, nor do I confine myself to the exact detail construction of said parts as illustrated in the accompanying drawings. 95

I claim:—

1. In a device of the kind described, a bayonet type tubular socket member having inwardly off-set leg members projecting longitudinally from its inner end, said leg members being spaced apart and together forming a socket standard, a coupling plate of insulating material slidably mounted on said socket standard for vertical movement toward and away from the inner end of said 105 socket member, means for connecting the lower ends of said leg members with a base, a compression spring intermediate said coupling plate and said base for yieldingly thrusting the coupling plate toward the socket member, said coupling plate having an opening therein, a service wire electrode to project through said coupling plate opening toward said socket member, a yieldable means mounted on said coupling plate to 110 grasp said service wire electrode to detachably retain the same coupled to said coupling plate, and said service wire electrode having a contact point adapted to be held by the spring thrust movement of said coupling plate in electrical engagement with the terminal means of a lamp inserted in said socket member.

2. In a device of the kind described, a bayonet type tubular socket member having inwardly off-set leg-members projecting longitudinally from its inner end, said leg members being spaced apart and together forming a socket standard, a coupling plate of insulating material slidably mounted on said 125

- socket standard for vertical movement toward and away from the inner end of said socket member, means for connecting the lower ends of said leg members with a base, a compression spring intermediate said coupling plate and said base for yieldingly thrusting the coupling plate toward the socket member, said coupling plate having an opening therein, a service wire electrode to project through said coupling plate opening toward said socket member, a yieldable means mounted on said coupling plate to grasp said service wire electrode to detachably retain the same coupled to said coupling plate, said service wire electrode having a contact point directed toward the terminal means of a lamp inserted in said socket member, an insulated switch member movable across the inner end 20 of said socket member between the contact point of said service wire electrode and said lamp terminal means, and said slide switch member having a conductive switch contact extending therethrough adapted to be carried into and out of mutual interconnecting contact with said contact point of said service wire electrode and said lamp terminal means by the manipulated movement of said slide switch member.
3. In a device of the kind described, a bayonet type tubular socket member having inwardly off-set leg members projecting longitudinally from its inner end, said leg members being spaced apart and together forming a socket standard, a coupling plate of insulating material slidably mounted on said socket standard for vertical movement toward and away from the inner end of said socket member, means for connecting the lower ends of said leg members with a base, a compression spring intermediate said coupling plate and said base for yieldingly thrusting the coupling plate toward the socket member, said coupling plate having an opening therein, a service wire electrode to project through said coupling plate opening toward said socket member, a yieldable means mounted on said coupling plate to grasp said service wire electrode to detachably retain the same coupled to said coupling plate, said service wire electrode having a contact point directed toward the terminal means of a lamp inserted in said socket member, a slide switch member 40 diametrically arranged beneath said socket member, said socket member having opposed indented guide notches in its lower marginal end to receive said slide switch member subject to longitudinal movements across said socket member, said slide switch member being made of insulating material and having a conductive switch contact extending therethrough adapted to be carried into and out of mutual interconnecting contact with said contact point of said service wire electrode
- and said lamp terminal means by longitudinal movements of said slide switch member, and said slide switch member being retained by the spring thrust movement of coupling plate and the service wire electrode in operative assembled relation to the guide notches of said socket member.
4. In a device of the kind described, a socket member having leg members adapted to provide a standard therefor, a service wire electrode coupling means vertically 75 slidable on said standard, spring means for normally thrusting said coupling means toward the socket member, and spring gripping means for detachably engaging a service wire electrode with said coupling means, the spring thrust movement of said coupling means serving to hold said service wire electrode in electrical engagement with the terminal means of a lamp inserted in said socket member.
5. In a device of the kind described, a socket member having leg members adapted to provide a standard therefor, a service wire electrode coupling means vertically 90 slidable on said standard, spring means for normally thrusting said coupling means toward the socket member, and spring gripping means for detachably engaging a service wire electrode with said coupling means, 95 said service wire electrode having a contact point directed toward the terminal means of a lamp inserted in said socket member, an insulated switch member movable across the inner end of said socket member intermediate the latter and said coupling means, and said switch member having a conductive contact extending therethrough adapted to be carried into and out of mutual interconnecting contact with said contact point 100 of said service wire electrode and said lamp terminal means by the manipulated movement of said slide switch member.
6. In a device of the kind described, a socket member having leg members adapted 110 to provide a standard therefor, a service wire electrode coupling means vertically slidable on said standard, spring means for normally thrusting said coupling means toward the socket member, spring gripping 115 means for detachably engaging a service wire electrode with said coupling means, said service wire electrode having a contact point directed toward the terminal means of a lamp inserted in said socket member, 120 a slide switch member diametrically arranged beneath said socket member, said socket member having opposed indented guide notches in its inner marginal end to receive said slide switch member subject to 125 longitudinal movements across said socket member, said slide switch member being made of insulating material and having a conductive switch contact extending therethrough adapted to be carried into and out 130

of mutual interconnecting contact with said contact point of said service wire electrode and said lamp terminal means by longitudinal movements of said slide switch member, and said slide switch member being retained in assembled relation to the guide notches

of said socket member by the spring thrust movement of said coupling means.

In testimony, that I claim the invention set forth above I have hereunto set my hand this 9th day of September, 1924.

FREDERICK A. FAULHABER, JR.
